CLAIM

The ornamental design for a little dinosaur smart alarm clock, as shown and described.

DESCRIPTION

FIG. 1 is a front, right, and top perspective view of a little dinosaur smart alarm clock, showing our design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines shown in the drawings are included for the purpose of illustrating portions of the little dinosaur smart alarm clock that form no part of the claimed design.
